UNITED STATES PATENT OFFICE

1,962,053

METHOD OF REENFORCING INSOLES

Thomas A. Calnan, Montmorency, France, assignor to Boston Blacking & Chemical Co., a corporation of Massachusetts

Application June 15, 1932, Serial No. 617,466

2 Claims. (Cl. 12—146)

This invention relates to improvements in the manufacture of insoles and is illustrated herein with special reference to the reenforcement of economy insoles and to the preparation of the 5 textile fabric with which the insoles are reenforced.

Objects of my invention are to provide a method of reenforcing insoles with textile fabric such as duck by which it is practicable to eliminate 10 the application of a coat of adhesive to the face of the duck prior to the coating which is applied by the shoe manufacturer, and to prevent, in a simple and inexpensive manner, ravelling of the 15 cut edges of strips of uncoated textile fabric which may be used in said insole reenforcing method.

With the above and other objects in view the invention will now be described with reference to the accompanying drawing and pointed out in 20 the claims.

In the drawing,

Fig. 1 illustrates the application by spraying of discrete particles of a suitable adhesive on to an end surface of a roll of duck;

Fig. 2 illustrates the applying or a coating of adhesive to a strip of duck the edges of which have been prevented from ravelling in the manner illustrated in Fig. 1, and also illustrating the applying of the strip to an insole and the severing from the strip of a portion of sufficient length to reenforce the insole;

Fig. 3 illustrates the forming of the cut-off portion of the material against the inner face of the rib of the insole and against the bottom of the insole by means of a hand tool; and

Fig. 4 illustrates the operation of further forming the reenforcing material to the insole and trimming off the excess of the reenforcing material flush with the outer edge of the rib of the insole by the operating instrumentalities of an insole reenforcing machine.

The roll 10 in Fig. 1 comprises a continuous strip 12 of uncoated duck cut from relatively wide webbing as disclosed in Ellis Patent No. 1,830,428, to a width suitable to the reenforcement of an insole, as indicated in Fig. 3, and of such length as to provide a roll of convenient size, say a foot, more or less, in diameter. Separate, discrete particles of adhesive, illustrated at 14 in Fig. 1, are applied to the ends of the roll and distributed substantially uniformly thereover, as by means of a spray gun of well-known character, illustrated at 16 in Fig. 1, whereby the edge or marginal threads are adhesively bonded 55 to the body of the fabric. While various types

of adhesive may be used for this purpose I prefer to use a suitably protected water dispersed rubber cement or latex, compounded either from the natural latex of a rubber tree such as the *Hevea brasiliensis* or from an artificial water dispersion of previously coagulated rubber, both of which are to be considered as within the meaning of the word "latex" as used herein. An example of such a protected latex adhesive may be made by mixing 9 parts by volume of a 35 60 degrees Beaumé sodium silicate solution, 9 parts of protected latex, compounded as hereinafter described, and 2 parts of water, thereby providing a solution which can be sprayed readily and of such a nature that the non-coalescing, discrete particles of adhesive on the ends of the roll will adhere firmly, sinking into the material sufficiently to bond the edge or marginal threads to the body of the fabric without bonding together the edge threads of successive fabric layers, 70 thereby preventing ravelling without, however, producing any considerable resistance to the unwinding of the roll or requiring excessive effort on the part of the operator who pulls the material manually through the coating apparatus in the 80 shoe factory. Such an adhesive, moreover, is long lived and will not deteriorate even if the material is stored for an abnormally long time.

The protected latex referred to above may be made up from the following ingredients: 85.

Oil of camphor	5 liters
Oil of citronella	.1 liters
Benzol	1.5 liters
Ammonium sulphoricinate	1.5 liters
Nekal or neomerpin	200. grams 90.
Latex (60% rubber content)	20. liters

This is compounded by adding the oil of camphor and oil of citronella to the benzol. This mixture is then added to the ammonium sulphoricinate (sulphonated castor oil neutralized with ammonia). The Nekal or Neomerpin (a well-known emulsifier comprising the disulphonic acid salt of hexaline which is a sulphonated product of hydrogenated naphthalene or phenol) is dissolved in about 2 liters of hot water to which is added cold water to make up to about 6½ liters which is then added to the mixture of oil of camphor, oil of citronella, benzol and ammonium sulphoricinate. When these two solutions have been well mixed they should be added to the latex, stirring slowly but thoroughly. 100

In this composition the principal adhesive value is obtained from the rubber of the latex, the sodium silicate serving both as an adhesive and 110

to protect the latex. The oil of camphor and oil of citronella improve the flow of the material and thereby help it to spray well. The benzol softens the rubber causing it to swell and helps the adhesive to dry quickly. If preferred toluol may be used in place of benzol. Ammonium sulphoricinate softens the rubber and increases its adhesiveness. The Nekal or Neomerpin acts as an emulsifier and together with the sodium silicate enables the adhesive to be stored for a reasonable time before it is sprayed.

Another variety of protected latex which may be used for this operation is one the rubber particles of which are protected with a casein-formaldehyde condensation product adsorbed on the surface of the particles, the adhesive containing only a small proportion of the casein formaldehyde condensation product as compared to the rubber. Such an adhesive, diluted sufficiently to be readily sprayable, will be found effective for the present purposes.

The uncoated fabric the cut edges of which are prevented from ravelling by this treatment may be handled and applied to the insoles in the manner disclosed in the Ellis Patent No. 1,830,428, except that the coating of adhesive, which preferably contains a substantial proportion of rubber, and which is applied to the fabric immediately before it is applied to the insole, can advantageously be somewhat thicker.

The treated rolls of slitted duck wherein the marginal threads are adhesively bonded to the body of the otherwise uncoated fabric are purchased by the shoe manufacturer who passes the strip progressively through a suitable coating apparatus, illustrated at 18 in Fig. 2, wherein the strip of fabric is closely engaged by cooperating members, and adhesive, preferably containing a substantial proportion of rubber, applied to one side of the closely-engaged fabric. This apparatus may be of the character disclosed in Letters Patent of the United States No. 1,771,388, granted July 22, 1930, on an application filed in the name of Russell K. Nash, or of the character disclosed in Letters Patent of the United States No. 1,898,383, granted February 21, 1933, on another application filed in the name of said Nash. In the operation of both of the above-mentioned coating devices the fabric moves between lateral guide members cooperating with the marginal portions of the fabric during the application of the adhesive thereto. The end portion 19 of the strip 12, which is coated on its upper surface in the manner hereinabove described, is laid out on a bench or table 20 (Fig. 2) and a suitably prepared insole 22 is applied to the coated end of the strip. As illustrated, the insole is provided with a lip or rib 21. This lip and the shank and forepart of the insole are to be reenforced but the heel seat portion 24 is to be left bare. After the insole has been applied to the end of the strip the desired portion of the strip is severed, as indicated at 26. The insole is then turned over and the severed portion 28 (Fig. 3) is formed to the lip 21 of the insole by boning down with a hand tool 30. Then the material is further formed to the lip of the insole and the surplus which extends beyond the lip of the insole is trimmed off, for example with the aid of an insole reenforcing machine such as that disclosed in Letters Patent of the United States No. 1,726,800, granted September 3, 1929 on an application filed in the name of Frederic E. Bertrand. Such machine forming and trimming of the material is

illustrated in Fig. 4 in which the marginal portion of the insole is held between driven rolls 32 and 34 while the reenforcing material is tucked in the angle between the rib and the bottom of the insole by a driven roll 36. The portion of the reenforcing material which extends beyond the outer edge of the lip is trimmed off by a rapidly rotating disk knife 38.

Certain of the advantages of my invention as compared with prior art practices will now be apparent. Prior to my invention, when a strip of uncoated fabric having cut edges was drawn through an adhesive-applying device wherein the fabric is closely engaged by cooperating and lateral guide members, the marginal threads loosened or ravelled. Many of these loosened threads in fairly short lengths became separated from the body of the fabric. Certain of these loosened threads became admixed with the adhesive composition and were distributed over the adhesive-coated surface of the fabric. When such fabric was applied to the insole these scattered threads provided undesirable ridges and to avoid this result it was necessary to remove these threads individually from the fabric before application to the insole, a process time consuming and expensive. Other loosened threads served to clog the adhesive-applying machine, rendering difficult the application of adhesive in predetermined uniform quantity and necessitating frequent dismantling and cleaning of the adhesive-applying device. By my invention, on the other hand, wherein the marginal portions of the uncoated fabric are adhesively bonded to the body of the fabric, such loosening of the edge threads is minimized or substantially prevented, while the necessity of pre-coating the fabric is obviated.

Furthermore, according to another feature of the invention, wherein the edge or marginal threads of a roll of fabric are bonded to the body of the fabric by separate, discrete particles of adhesive, ravelling is prevented or minimized when the roll is unwound, partly by reason of the fact that the threads of successive superimposed layers of fabric are not bonded together, as occurs when a continuous layer of adhesive is applied to the sides of a roll with the accompanying result of increased, rather than decreased, ravelling upon unwinding the fabric.

Having thus described my invention what I claim as new and desire to secure by Letters Patent of the United States is:

1. That improvement in methods of reenforcing insoles which comprises providing a continuous strip of uncoated duck having cut edges and having its marginal threads adhesively bonded to the body of said duck, drawing said duck progressively between members closely engaging the strip of duck over substantially its entire width and applying adhesive to the closely-engaged duck and affixing the adhesive-coated duck to insoles.

2. That improvement in methods of reenforcing insoles which comprises providing a continuous strip of uncoated duck having cut edges and having its marginal threads adhesively bonded to the body of said duck, drawing said duck progressively between lateral guide members cooperating with the marginal portions of the duck and applying adhesive to the laterally-guided duck, and affixing the adhesive-coated duck to insoles.

THOMAS A. CALNAN.
